UNITED STATES PATENT OFFICE.

NATHANIEL W. KAHLE, OF FRAMPTON, PENNSYLVANIA.

WRENCH.

SPECIFICATION forming part of Letters Patent No. 761,383, dated May 31, 1904.

Application filed September 30, 1903. Serial No. 175,191. (No model.)

To all whom it may concern:

Be it known that I, NATHANIEL W. KAHLE, a citizen of the United States, residing at Frampton, in the county of Clarion and State 5 of Pennsylvania, have invented certain new and useful Improvements in Wrenches; and I do declare the following to be a full, clear, and exact description of the invention, such as will enable others skilled in the art to 10 which it appertains to make and use the same, reference being had to the accompanying drawings, and to letters of reference marked thereon, which form a part of this specification.

15 This invention relates to new and useful improvements in sliding-jaw wrenches; and it comprises a stationary jaw with serrated shank portion and a movable jaw having a cam-lever pivoted to the same and adapted to 20 frictionally engage one face of the shank portion of the fixed jaw, while means is provided for holding a lug on said lever in a longitudinal groove in the shank portion, whereby the parts may be held securely while operating 25 the wrench.

The invention consists, further, in various details of construction and in combinations and arrangements of parts, as will be herein-after fully described and then specifically de- 30 fined in the appended claim.

35 My invention is illustrated in the accompanying drawings, which, with the letters of reference marked thereon, form a part of this application, and in which drawings Figure 1 is a side elevation of my improved wrench, showing the sliding jaw locked. Fig. 2 is a central longitudinal section through the wrench and the jaws.

Reference now being had to the details of 40 the drawings by letter, A designates a fixed jaw of a wrench, having a shank portion B, with teeth or serrations C on one face thereof, and upon the rear face of the shank portion is a longitudinal groove E. One end of the 45 fixed jaw is curved, as at A', to coöperate with a serrated jaw F upon the sliding jaw, adapting the device for use as a pipe-wrench, said jaw F being preferably dovetailed to the sliding jaw and having a slight longitudinal move- 50 ment. Said sliding jaw (designated in the

drawings by letter H) is chambered out to receive the shank portion of the fixed jaw and has a series of serrations H' along the inner marginal edge of the chambered portion to engage the teeth C upon the shank portion of 55 the fixed jaw.

A lever K, having a cam K' at one end, is pivoted on a pin L, mounted within the walls of the sliding jaws. The cam portion of said lever is designed to frictionally engage the 60 rear face of the shank portion of the fixed jaw to hold the wrench in an adjusted relation. Said shank portion is guided in its longitudinal movements through the chambered portion of the movable jaw by means of a pin 65 O, passed through the walls of the movable jaw, and the inner face of said cam-lever is grooved, as at Q, transversely to receive said pin when the lever is closed, and R designates a lug upon the under face of the lever 70 K, which lug is adapted to rest in said slot E when the lever and handle are brought together, thus securely holding the wrench from lateral strain in operation.

From the foregoing it will be observed that 75 by the provision of a wrench embodying the features shown and described means is provided for quickly and easily adjusting the wrench without the necessity of turning screws or nuts, as the sliding jaw may be 80 readily adjusted to any position by throwing the lever outward and pushing the sliding jaw forward or backward upon the shank portion of the fixed jaw, and when the lever is thrown against the shank portion of the fixed 85 jaw the jaws will be securely held in an adjusted position.

While I have shown a particular form of construction of wrench embodying the features of my invention, it will be understood 90 that I may make alterations, if desired, in the detailed construction of the same without in any way departing from the spirit of the invention.

Having thus fully described my invention, 95 what I claim as new, and desire to secure by Letters Patent, is—

A sliding-jaw wrench comprising a fixed jaw with a shank portion having serrations 100 on one edge and an elongated recess in its

opposite edge, a movable jaw chambered out and mounted upon the shank portion of the fixed jaw, serrations on the inner wall of the sliding jaw, a pin Q mounted in the walls of 5 the sliding jaw, a lever pivoted to the walls of the sliding jaw and having a cam extending beyond the inner marginal edge of the handle of said lever, and a recessed portion O adapted to receive said pin when the lever is

thrown toward the shank portion of the fixed 10 jaw, and a lug R upon said lever adapted to engage said elongated recess, as set forth.

In testimony whereof I hereunto affix my signature in presence of two witnesses.

NATHANIEL W. KAHLE.
